CLAIM

The ornamental design for a shrub rake as shown and described.

DESCRIPTION

FIG. 1 is perspective view of the shrub rake showing our new design;

FIG. 2 is a front view thereof;

FIG. 3 is a rear view thereof;

FIG. 4 a right side view thereof;

FIG. 5 is a left side view thereof;

FIG. 6 is a top view thereof; and,

FIG. 7 is a bottom view thereof.

The portions of the article in broken lines in the drawings form no part of the claimed design. The dash-dot broken lines shown in the drawings depict environment that forms no part of the claimed design.

1 Claim, 5 Drawing Sheets
